(57) **CLAIM**

The ornamental design for an electronic camera, as shown and described.

DESCRIPTION

FIG. 1 is a top, front and side perspective view of an electronic camera showing my new design;

FIG. 2 is a front elevational view thereof;

FIG. 3 is a top plan view thereof;

FIG. 4 is a bottom plan view thereof;

FIG. 5 is a side elevational view thereof from the left of FIG. 2; and,

FIG. 6 is a side elevational view thereof from the right of FIG. 2.

The structure shown in broken line illustrates the environment of the present invention and is not claimed in the present application.
